UNITED STATES PATENT OFFICE.

JAMES SCOTT, OF ARAPAHOE COUNTY, COLORADO.

AMALGAMATOR.

SPECIFICATION forming part of Letters Patent No. 243,802, dated July 5, 1881.

Application filed January 13, 1881. (Model.)

To all whom it may concern:

Be it known that I, JAMES SCOTT, of the county of Arapahoe and State of Colorado, have invented a new and useful Improvement 5 in Amalgamators for the purpose of saving gold, either in placer-mines or stamp-mills; and I do hereby declare that the following is a full, clear, and exact description of the construction and operation of the same, reference being had to the annexed drawings, making part of this specification, in which—

Figure 1 is a perspective view; Fig. 2, section view.

A is the frame of the machine.

15 B is a double sieve or rocker hung on pivots connected by a crank and rod to give it a rocking motion. The rocker is a box with solid bottom, having an outlet at one end, and two perforated sieves, which may be made by 20 punching or drilling holes in metal, or by laying bars of iron across the box, and are adjustable to different angles, according to the kind of dirt running through, each having an orifice for disposing of refuse.

25 C' C² C³ C⁴ are amalgamating plates, set on an incline to allow dirt and water to flow off.

D D are a set of corrugated rolls.

30 E' E² are disks of amalgamated copper cut and bent to form wings, and are set in a trough or box and rotate, thereby mixing up the mud.

F is a four-leaved fan set with magnets.

35 G G is a fan set so as to mesh in F and rotate it.

The operation of the machine is as follows:

35 The dirt and water are thrown in B, the boulders passing out at K, the finer portions passing through the sieve H. The dirt is then passed through a still finer sieve, I, then down M onto amalgamating-plates, the refuse passing out at L. The dirt and water flow over amalgamating-plate C' through roller D D, which thoroughly crushes it, and should any rusty gold, or gold embedded in sand, rock, or other substance, be present, new surfaces will 40 be formed, thereby giving the amalgamation

a chance to hold the gold. Passing through rolls D D the dirt flows over amalgamating-plate C², thence into trough O', and, being mixed by amalgamated wings E', which will catch all floating gold, passes thence from 50 trough O' over plate C³ into trough O², and again is mixed by amalgamating-wings E², thence over amalgamating-plate C⁴, through outlet P on magnet-wheel F, which will hold black sand or any rusty gold that should pass 55 through, the refuse, which will not adhere to it, dropping off as it rotates, the black sand and rusty gold being wiped off by fan G and deposited on the other side.

I am aware of the patent to Testman, No. 60 56,636, July 24, 1866, and I claim nothing therein shown.

I claim—

1. In an amalgamator constructed substantially as described, the fan G, having amalgamated flat wings or leaves, as herein described, for the purpose set forth.

2. In an amalgamator, the combination, with the fan F, having magnetic wings or leaves, of the amalgamated fan G, arranged to remove 70 from fan F the black sand or rusty gold which may adhere to the latter, as set forth.

3. The magnetic fan F, arranged as herein described to intersect and be operated by the leaves of an amalgamated fan, G, for the purpose shown and specified.

4. In an amalgamator, the crushing-rollers D D, fluted or corrugated, as shown, and arranged between the inclined amalgamated plates C' C², as herein described, for the purpose set forth.

5. The combination of the box B, sieves H and I, plates C' C² C³ C⁴, rolls D D, wing fans or mixers E' and E², magnet-wheel F, and fan G, for the purposes set forth and specified.

JAMES SCOTT.
